(57) **CLAIM**

I claim the ornamental design for a clamp, as shown and described.

DESCRIPTION

FIG. 1 Is a front left perspective view of a clamp, showing my new design;

FIG. 2 Is a side view thereof;

FIG. 3 Is a side view thereof;

FIG. 4 Is a back view thereof;

FIG. 5 Is a front view thereof;

FIG. 6 Is a bottom plan view thereof, shown at a larger scale;

FIG. 7 Is a top plan view thereof, shown at a larger scale;

FIG. 8 Is a front left perspective view of the clamp extended;

FIG. 9 Is a side view thereof;

FIG. 10 Is a side view thereof;

FIG. 11 Is a back view thereof;

FIG. 12 Is a front view thereof;

FIG. 13 Is a bottom plan view thereof, shown at a larger scale;

FIG. 14 Is a top plan view thereof, shown at a larger scale;

FIG. 15 Is a front left perspective view of the clamp lowered;

FIG. 16 Is a side view thereof;

FIG. 17 Is a side view thereof;

FIG. 18 Is a back view thereof;

FIG. 19 Is a front view thereof;

FIG. 20 Is a bottom plan view thereof, shown at a larger scale;

and,

FIG. 21 is a top plan view thereof, shown at a larger scale.

The features shown in broken lines depict environmental subject matter only and form no part of the claimed design.
